D. Carroll.
Loom Shuttle.

N° 10,335.

Patented Dec. 20, 1853.

Fig. 1.

Fig. 2.

UNITED STATES PATENT OFFICE.

DAVID CARROLL, OF BALTIMORE, MARYLAND.

SHUTTLE.

Specification of Letters Patent No. 10,335, dated December 20, 1853.

To all whom it may concern:

Be it known that I, DAVID CARROLL, of Mount Vernon, in the city of Baltimore and State of Maryland, have invented certain 5 new and useful Improvements in Shuttles; and I do hereby declare the following to be a full, clear, and exact description of the same, reference being had to the accompanying drawings, making a part thereof, in 10 which—

Figure 1, represents a longitudinal vertical section through the center of the shuttle, and Fig. 2, represents a top view of the shuttle complete.

15 Similar letters in both the figures refer to like parts.

The nature of my invention relates to the method of preventing the thread from looping when it pays off too fast from the 20 bobbin.

To enable others skilled in the art to make and use my invention, I will proceed to describe the same with reference to the drawings.

25 The body A, of the shuttle is similar in form to the ordinary shuttle, except that the bottom is entirely closed.

B, is the bobbin upon which the yarn is wound, and is held in the shuttle by the 30 spindle C, and spring catch D. In front of the point of the bobbin is a hinged guard piece E, the lower part F, of which rests against a spring G, so as to hold the guard piece open or shut as may be desired for 35 placing or shielding the point of the bobbin. The thread a from the bobbin passes through a hole b, in the guard plate and thence through a ring H, and under a spring brake to give it even tension.

40 It is well known that at times the thread or yarn pays off too fast from the bobbin, and the rapid movement of the shuttle

throws out the slack of the thread and yarn and causes looping or tying over the shuttle, which sometimes proves destructive to the 45 web. It is to avoid this difficulty that I have devised the guard plate.

I am aware that a pin or pins have been permanently arranged across the box of the shuttle for preventing this evil, and also 50 that, a slide has been used, but both these were, and of necessity had to be, placed in front of the point of the bobbin, so that the bobbin could swing into and out of the box. But neither of these devices overcomes the 55 difficulty of looping with any degree of certainty.

The hinge of my cap or guard E, is in front of the point of the bobbin, but the guard itself extends back over the point of 60 the bobbin, as seen in the drawing to prevent entirely the thread or yarn which must pass off from the point of the bobbin, from getting back far enough, to throw out from the shuttle, and by this means I entirely over- 65 come the evil.

I would state that a closed shuttle has been used for running cloth where a cap instead of a bobbin is employed; this I do 70 not claim, but

What I do claim therein as new and desire to secure by Letters Patent is,

In combination with the bobbin of an ordinary shuttle, the hinged guard, projecting from and over the point toward the heel 75 of the bobbin, for the purpose of preventing the thread or yarn when paying off too fast, from looping or tying substantially as described.

DAVID CARROLL.
